UNITED STATES PATENT OFFICE.

WILLIAM BREDE, OF HONOLULU, HAWAIIAN ISLANDS.

RATCHET-DRILL.

SPECIFICATION forming part of Letters Patent No. 292,280, dated January 22, 1884.

Application filed March 21, 1883. (No model.)

To all whom it may concern:

Be it known that I, WILLIAM BREDE, of Honolulu, Oahu, Hawaiian Islands, have invented a new and Improved Ratchet-Drill, of 5 which the following is a full, clear, and exact description.

In my improved ratchet-drill a continuous rotary motion of the drill can be obtained by a forward and backward movement of the lever 10 of the ratchet, and the drill fed automatically at the same time, whereby drilling can be done quickly and readily.

The invention consists in a combination of bevel-gearing and ratchet mechanism for operating the drill and effecting the feed, as hereinafter described and claimed.

Reference is to be had to the accompanying drawings, forming part of this specification, in which similar letters of reference indicate corresponding parts in all the figures.

Figure 1 is a side elevation of my improved brace. Fig. 2 is a longitudinal section of the same, and Fig. 3 is a cross-section on line $x-x$ of Fig. 1. Fig. 4 is a detail sectional view, 25 showing the position of the slide and a sectional view of the cam.

A is the frame, formed with an upper bearing, l , and lower bearing, l' , connected by a side arm.

30 C is the spindle, extending through the lower bearing, l' , and into the upper bearing, l .

J is a screw-stem fitted loosely in the upper bearing, l , and extending at its lower end into the spindle C, which is formed hollow to receive the stem. The screw-stem is prevented 35 from turning by a feather, w , on the spindle entering a slot, w' , formed in the screw.

On the screw, above frame A, is a loose collar, M, beneath a nut, L, that is formed with 40 ratchet-teeth on its under side.

m is a pawl fitted in a recess in collar M, and forced upward by a spring into engagement with the teeth on nut L.

n is a thumb-piece for depressing the pawl 45 to allow backward movement of the nut.

Fixed on spindle C, above bearing l' , is a bevel-pinion, D, and a ratchet-wheel, a' , that is fast on the hub of the pinion.

E is a bevel-pinion loose on the spindle, and 50 having a ratchet-wheel, a , on its hub, and on

the spindle between the ratchet-wheels is hung the operating-lever B, provided with pawls b b' , engaging ratchet-wheels a a' , the teeth of which are in reverse.

F is a bevel-pinion fitted loosely, as shown 55 in Fig. 2 of the drawings, in the frame A, so as to engage the pinions D E. The upper side of pinion E is notched or toothed to form a cam, E', and on frame A is a slide, H, having its lower end engaging the cam of the pinion, 60 while its upper end is made with an inclined slot, s, engaging a pin, t, projecting from collar M.

I is a cam-sleeve loose on frame A, supporting the slide H by a pin, u, projecting from 65 the slide over the sleeve I, so that by turning the sleeve the slide will be raised and lowered, and its length of movement by the cam thus regulated. A spring, e, in a groove around the frame A bears on a pin, u', projecting 70 from the slide, for the purpose of keeping the slide down.

In the operation of the drill, lever B being moved in one direction, one pawl, b , acting on ratchet-wheel a , rotates pinion E, and the motion is transmitted through pinions F D to spindle C. The lever, on its return movement, 75 acts by pawl b' on ratchet a' , thereby further rotating pinion D, and keeping up the movement of spindle C in the same direction as before.

In the movement of pinion E its cam-hub causes the rise of slide H, more or less continuously, and a greater or less distance, according to adjustment of sleeve I, thereby moving collar M and causing movement of nut L, so that the screw J is forced up at each rise of the slide. The return movement of the collar M is caused by spring e.

The upper end of screw J is squared to receive 90 a concave cap, K, for holding the drill, and the cap is formed with points to prevent its revolving while drilling.

Having thus described my invention, what I claim as new, and desire to secure by Letters 95 Patent, is—

1. In ratchet-drills, the combination of cam-pinion E, slide H, collar M, nut L, and screw J, substantially as shown and described.
2. In ratchet-drills, the cam-sleeve I, com- 100

combined with slide H, cam-pinion E, and collar M, substantially as and for the purpose specified.

3. In ratchet-drills, the spring e, combined with feed-slide H, having a pin thereon, and cam-pinion E, as and for the purpose specified. The foregoing specification of my improve-

ment in ratchet-drill brace signed by me this 17th day of February, 1883.

WILLIAM BREDE.
